(57) **CLAIM**

The ornamental design for a vacuum cleaner, as shown and described.

DESCRIPTION

FIG. 1 is a front elevational view of a vacuum cleaner showing our new design;

FIG. 2 is a rear elevational view thereof;

FIG. 3 is an enlarged right side view thereof;

FIG. 4 is an enlarged left side view thereof;

FIG. 5 is a top plan view thereof;

FIG. 6 is a bottom plan view thereof;

FIG. 7 is a perspective view thereof;

FIG. 8 is another perspective view thereof;

FIG. 9 is an enlarged view of portion 9 shown in FIG. 1;

FIG. 10 is an enlarged view of portion 10 shown in FIG. 6; and,

FIG. 11 is an enlarged view of portion 11 shown in FIG. 7. The broken lines illustrate portions of the vacuum cleaner that do not form part of the claimed design.

The dash-dot lines illustrate boundaries of the enlarged portions and do not form part of the claimed design.

1 Claim, 11 Drawing Sheets
